US0D1085429S

(12) **United States Design Patent** (10) **Patent No.:** **US D1,085,429 S**
(45) **Date of Patent:** **** Jul. 22, 2025**

(54) **TOE CORRECTOR**

(71) Applicant: **Dongguan Baifangyi Health Technology Co., Ltd.**, Dongguan (CN)

(72) Inventor: **Mei'e Huang**, Dongguan (CN)

(73) Assignee: **Dongguan Baifangyi Health Technology Co., Ltd.**, Dongguan (CN)

(**) Term: **15 Years**

(21) Appl. No.: **29/919,846**

(22) Filed: **Dec. 6, 2023**

(30) **Foreign Application Priority Data**

Nov. 16, 2023 (CN) 202330751130.9

(57) **CLAIM**

The ornamental design for a toe corrector, as shown and described.

DESCRIPTION

FIG. 1 is a front perspective view of a toe corrector showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view taken from circle 9 in FIG. 1; and,

FIG. 10 is a partial enlarged view taken from circle 10 in FIG. 1.

The dash-dot broken lines in the drawings depict the portions of the toe corrector that form no part of the claimed design.

(Continued)

The dot-dash broken lines in the drawings depict the boundaries of the partial enlarged views that form no part of the claimed design.
